[57] CLAIM

The ornamental design for a stocking removing tool for the handicapped or similar article, substantially as shown and described.

DESCRIPTION

FIG. 1 is an isometric view of a stocking removing tool for the handicapped or similar article showing my new design.

FIG. 2 is a top plan view thereof.

FIG. 3 is a side elevational view thereof, taken in the direction of the arrow 3 in FIG. 2.

FIG. 4 is an opposite side elevational view thereof.

FIG. 5 is a bottom plan view thereof.

FIG. 6 is an end elevational view thereof on a different scale, as seen from the left of its FIG. 2 position.

FIG. 7 is an end elevational view thereof on the same scale as FIG. 6, as seen from the right of its FIG. 2 position.

FIG.4.

FIG.1.

FIG.2.

FIG.3.

FIG.5.

FIG.6.

FIG.7.
